CLAIM

The ornamental design for a tool for rotation, as shown and described.

DESCRIPTION

FIG. 1 is a rear perspective view of a tool for rotation showing our design;

FIG. 2 is a front perspective view thereof;

FIG. 3 is another rear perspective view thereof;

FIG. 4 is another front perspective view thereof;

FIG. 5 is a front view thereof;

FIG. 6 is a right side view thereof, which is a mirror image of the left side view thereof;

FIG. 7 is a rear view of the tool of FIG. 5; and,

FIG. 8 is a bottom view of the tool of FIG. 6.

The broken lines in the drawings depict unclaimed environmental subject matter.
